UNITED STATES PATENT OFFICE.

JACOB WILLIAMS, OF DUBLIN, INDIANA.

CULTIVATOR.

SPECIFICATION forming part of Letters Patent No. 253,458, dated February 7, 1882.

Application filed October 13, 1881. (Model.)

To all whom it may concern:

Be it known that I, JACOB WILLIAMS, a citizen of the United States, residing at Dublin, in the county of Wayne and State of Indiana, have invented certain new and useful Improvements in Straddle-Row Cultivators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to straddle-row cultivators, and has for its object to furnish a sulky which can be used without the use of a tongue or other similar pole extended from the axles to the breasts of the horses.

It consists in a substantial frame which passes under and to the rear of the axle, and is made fast to the latter and to the arch, and is provided with a cross-bar, which passes under the forward end of the cultivator-beam, and has its forward end extended and provided with means for holding the whiffletree.

In the drawings, Figure 1 is a perspective of my invention, and Figs. 2 and 3 are detail views of parts thereof.

a' are the spindles or axles which carry the wheels. The inner end of axle *a* is bent to a vertical position, so as to provide the standard *a*², and is also bent horizontally to provide the top cross-bar, *a*³, which extends over the row of corn. The axle *a'* has its inner end bent to a vertical line, so as to provide a standard, *a*⁴, parallel with the standard *a*². The standard *a*⁴ has formed on its upper end an eye, *a*⁵, which slides over the end of the top bar, *a*³. The sides of the head or upper end of standard *a*⁴ are flattened, as shown in Fig. 2, and the ears of the clips, hereinafter described, project along these flattened sides and hold the standard to its position, and yet permit the standard to have a slight rocking motion on the arm *a*³. The top bar, *a*³, may be made rectangular or round. I prefer to make it round, so that the eye will turn thereon. The standard *a*⁴ is secured to the top bar, *a*³, so that it will swing slightly forward and back, and thus give a reciprocating movement between the two standards, so that there will be an adaptation or ad-

justment to the slight variations which take place between the draft of the two horses.

In my device I provide two clips, *c c*, constructed to slide over the bar *a*³, and flattened to fit snugly against the opposite sides of the eye *a*⁵ and hold the latter, so that the standard *a*⁴ will have the requisite swinging movement. The clips are held by pins *c*², which are put through suitable holes and through holes formed in the cross-bar *a*³. A series of holes are provided in the cross-bar *a*³, so that the eye *a*⁵ may be moved and fixed at any desired place, and thereby set the standards *a*² and *a*⁴ nearer together or farther apart, as may be required.

d is the supporting-frame, which is composed of the main straight bar *d*' and the lateral bar *d*². The main bar *d*' has its forward end arranged in proper position to have a whiffletree hooked thereon. The rear end of this bar passes under and several inches to the rear of the axle *a*, and is made fast to the latter by clips or other suitable fastenings. The lateral bar *d*² has its forward end secured near to the forward end of the main bar, while its rear end is carried to and past the inner side of the standard *a*², and is made fast to the latter by a clip, as shown. The ends of the bars *d*' *d*² which project to the rear of the axle are connected together by a cross-bar, *d*³, thus completing the frame *d*. The cross-bar *d*³ passes under the forward end of the cultivator-beam *e*, or under the clevis on the axle to which the beam is fastened.

The coupling *f* is journaled on the axle *a* and has on its top a slot, through which projects a pin or stud, *f*', fixed on the axle. The slot and pin are arranged so as to permit a limited turning movement to the coupling, which movement permits the cultivator to be lifted over obstructions. The clevis has in its rear end a horizontal slot, in which is pivoted the forward end of the beam *e*, thus giving the latter a lateral swinging movement. It will be seen that the weight of the beam *e* rests on the cross-bar *d*³.

When the horses are attached to the front end of the frame *d* the counter-balance between the draft of the horses and the weight of the cultivators holds the arch of the sulky in an upright position. When standing still the arch

will be held erect by the weight of the forward end of the frame, counterbalanced by the weight of the cultivators.

I have described only one frame, d . It will be seen that I employ two frames; but both being alike in construction and arrangement, the one description will answer for both.

It will also be seen that the arch of the sulky is composed of the standards a^2 a^4 and the cross-bar a^3 , united together adjustably, as hereinbefore described.

The supporting-wheels of the sulky have been omitted in the drawings, in order that the other parts may be more clearly brought to view.

It will be seen that I have here provided a substantial sulky for straddle-row cultivators and have dispensed with a tongue.

Having thus described my invention, what I claim, and desire to secure by Letters Patent, is—

1. The combination of the axle, provided with

pin f' , the coupling f , journaled on said axle, and provided with slot f^2 , the beam e , pivoted to the coupling f , and the cross-bar d^3 of the frame d , extended under and arranged to support the rear end of the coupling, substantially as set forth. 25

2. The combination, substantially as hereinbefore set forth, of the arched bar a^3 of axle a , provided with a series of vertical holes, the upright bar a^4 of axle a' , provided with eye a^5 , and the clips c , provided with parallel ears projected part way across the flattened sides of bar a^4 , and the pins c^2 , as set forth. 30

In testimony whereof I affix my signature in presence of two witnesses on this 10th day of October, 1881. 35

JACOB WILLIAMS.
